UNITED STATES PATENT OFFICE.

NORBERT LOCHBAUM, OF BERLIN, GERMANY.

DESIGN FOR A PHOTOGRAPHIC ALBUM.

SPECIFICATION forming part of Design No. 19,787, dated April 1, 1890.

Application filed January 27, 1890. Serial No. 338,290. Term of patent 3½ years.

To all whom it may concern.

Be it known that I, NORBERT LOCHBAUM, a subject of the German Emperor, residing at Berlin, in the Province of Brandenburg, Prussia, Germany, have invented and produced a new and original Design for Photographic Albums, of which the following is a specification.

Referring to the accompanying drawings, 10 Figure 1 is an outer side view of the album. Fig. 2 is a view of the album spread open.

The leading feature of my design consists in the outline shape of the album, the distinctive characteristic of which is that the 15 outline has a straight edge part *b* on one side, while the remainder has an orbicular shape with a serrated margin or edge, as shown.

The letter *A* designates the two covers of

the album, which are joined at the straight edge *b* on one side, and said straight edge 20 forms one side of the outline of a V-shaped end. Each cover has the same shaped margin or edge, and when closed the outline of the album will have a V-shaped end, one side of which is straight, and the remainder of the 25 outline will be orbicular in shape and have marginal serrations.

I claim—

A design for albums, as herein described and shown. 30

In testimony whereof I affix my signature in the presence of two witnesses.

NORBERT LOCHBAUM.
